Primary Examiner — Rashida Johnson

CLAIM

The ornamental design for an apparel, as shown and described.

DESCRIPTION

FIG. 1 is a perspective view of an apparel showing our new design;

FIG. 2 is a front view thereof;

FIG. 3 is a side view thereof, the opposite side being a mirror image thereof; and,

FIG. 4 is a rear view of the apparel.

The broken line showing of the remainder of the apparel is for environmental purposes only and forms no part of the claimed design.

1 Claim, 4 Drawing Sheets

FIG. 1

FIG. 2

FIG. 3

FIG. 4
